UNITED STATES PATENT OFFICE.

JAMES B. STETSON, JOHN HAMMOND, WILLIAM L. HOLMAN, AND JAMES W. HARRIS, OF SAN FRANCISCO, CALIFORNIA.

CABLE-GRIPPING MECHANISM.

SPECIFICATION forming part of Letters Patent No. 453,517, dated June 2, 1891.

Application filed November 22, 1889. Renewed April 27, 1891. Serial No. 390,651. (No model.)

To all whom it may concern:

Be it known that we, JAMES B. STETSON, JOHN HAMMOND, WILLIAM L. HOLMAN, and JAMES W. HARRIS, citizens of the United States, residing at San Francisco, in the county of San Francisco and State of California, have invented a new and useful Cable-Railway Car, of which the following is a specification.

Our invention relates to improvements in cable-gripping mechanism in which the grip is attached permanently to the passenger-car and generally known as "combination-cars;" and the objects of our improvements are, first, to construct a cable-railway car that need not be reversed at the terminus of a road by the employment of a turn-table, the latter method being now in general use for combination-cars; second, to provide better facilities for crossing the tracks of cable-car lines on intersecting streets when the car is ascending a steep grade adjoining such streets. We attain these objects by the construction illustrated in the accompanying drawings, in which—

Figure 1 is an elevation of the car, and Fig. 2 a plan of the same.

Similar letters refer to similar parts throughout the two views.

The car-frame consists of a flat platform of suitable length, having the body or upper structure constructed as described in our application for Letters Patent dated January 18, 1890.

A swinging truck E E is placed under each end of the car, as shown, allowing the car to turn curves on the road, said trucks being constructed on what is known as the "four-wheeled" or "bogie" style. Upon one of these trucks, which are otherwise similar, is placed the gripping mechanism or grip in the usual manner, and, as shown at D in compartment B, the grip being attached to the truck E, the shank of the grip extending downward and into the channel of the cable roadway between the rails, the jaws of the grip being shown in position for gripping the cable e. The lever f, with fulcrum at g, operates the grip in compartment B. In compartment C there is placed a lever h, with fulcrum at i, attached to the car-frame. This lever is connected at its short end j to the lever f in com-

partment B by the rod k, placed under the car-frame, said rod being forked at B and passing on each side of the king-bolt of the car. A flexible connection is put at l to allow side motion to rod k when the car is turning a curve on the road, the forked end of rod k being connected with lever f by the pin or bolt m at the point o. The gripping mechanism can consequently be worked from either end of the car; but as it is necessary to use one lever only when the car is going in a certain direction we make the lever f in such a manner that it may be removed when not in use. We do this by putting a socket on the lower end of said lever at o, into which the said lever is fitted, and is secured to said socket by the pin or bolt m at o, which pin or bolt also passes through and secures the forked end of rod k, as explained. When, therefore, we wish the car to run in the direction shown by the arrow in Fig. 1, we disconnect the rod k from the lever f with the pin m. The lever h is thereby rendered inoperative and the movements of the car are controlled by lever f. Upon reaching the terminus of the road the car is allowed to run upon the return-track through a switch arranged for that purpose, after which the pin m is removed and the lever f is taken out. The rod k is then connected at o and the pin m is replaced. This operation, requiring but a short space of time, places the grip under control of the lever h, the car now being ready to make the return trip.

It is obvious that a great advantage is obtained over the expensive and cumbersome turn-table method, which system of turning cars around occupies almost the full width of the street and obstructs the traffic at that point in addition to its being a costly method and in constant need of repairs.

It follows from the foregoing description that our car can be run in either direction along a line without turning it end for end, all that is necessary being a switch or cross-over connecting the forward and return tracks, this adaptability to circumstances being of great value when the tracks are so obstructed as to prevent further progress of the car, and such cases are of frequent occurrence during fires, public parades, &c. Assuming the car

to be running in a direction opposite to that of the arrow in Fig. 1 and ascending a steep grade immediately adjoining a cross-street upon which a cable railway is also in operation that our car is to cross, it is evident from the construction of our car with the gripping apparatus at the rear in this case that we can retain the hold upon the cable until our car has fully ascended the hill and is at least to half-way over the crossing, when the grip is to be released from the cable by the lever *h* to prevent contact with the above-mentioned cross-road cable.

This feature of our car insures greater safety and precision of action under the foregoing circumstances than is attained by cable cars now in use, in which the grip is always placed in the forward part of the car.

Having fully described our invention, what we claim, and desire to secure by Letters Patent, is—

1. In a cable-railway car, the combination of a gripping device placed at one end of the car with a lever at the opposite end of the car to operate said gripping device, both being connected by a rod *k* under the car-frame, as set forth.
2. The combination, in a cable-railway car, of a cable-gripping device placed upon a four-wheel swinging truck at one end of the car with a lever attached to the opposite end of the

car for operating the grip, said lever being connected at its short end with the main lever of the gripping mechanism by a rod placed under the car-frame, all substantially as described. 35

3. The combination, in a cable-railway car, of the gripping mechanism *D*, placed on a swinging truck at one end of the car, said gripping mechanism having a removable lever *f*, 40 socket *o*, and pin *m*, and connected to rod *k*, having forked end and flexible joint at *l*, with the lever *h* at the opposite end of the car, attached to the car-frame at the fulcrum *i*, said lever being connected at its short end to the 45 opposite end of rod *k*, substantially as described and set forth.

4. A car-body supported upon the independent swinging trucks *E* *E*, as shown, one at each end, in combination with a cable-gripping device *D*, supported on one of the trucks, the working-lever *f* of said gripping device being connected to an operating-lever *h*, attached to the car-frame at the opposite end by a rod *k*, as set forth. 50
